UNITED STATES PATENT OFFICE.

FRANK DUTCHER, OF VERSAILLES, PENNSYLVANIA.

RAILWAY-TORPEDO MACHINE.

No. 830,420.

Specification of Letters Patent.

Patented Sept. 4, 1906.

Application filed August 21, 1905. Serial No. 275,062.

To all whom it may concern:

Be it known that I, FRANK DUTCHER, a citizen of the United States, residing at Versailles, in the county of Allegheny and State 5 of Pennsylvania, have invented certain new and useful Improvements in Railway-Torpedo Machines, of which the following is a specification, reference being had therein to the accompanying drawings.

10 This invention relates to improvements in railway-torpedo machines, the object of which is to facilitate the connection of a rail-engaging member to the torpedo and to connect the two parts of the torpedo-case together, whereby time is saved and danger of exploding the torpedo prevented.

In the accompanying drawings, Figure 1 is a perspective view of a machine embodying my invention, the torpedo being acted upon 15 shown in position. Fig 2 is a top plan view, partially in section. Fig. 3 is an end elevation looking in the direction indicated by arrow in Fig. 2.

This machine is for use in connection with 20 metallic torpedoes consisting of an outer case 1 and an inner case 2. The outer case is provided with projecting ears 3, and the detonating material is placed between these two cases. The ears 3 perform a double function. They serve to unite a strap 4 to the 25 torpedo, by means of which the torpedo is connected to the tread of a railroad-rail, and they also serve to unite and hold the two parts of the torpedo-case together.

30 Referring now to the machine for closing down the ears and holding the strap 4 to the torpedo and connecting the two parts of the case together, which constitutes my present invention, it is provided with a recess 5, in 35 which the torpedo is placed, as shown clearly in Fig. 1. This recess constitutes a holder for the torpedo. Located at opposite sides of this holder are two oscillating presser-arms 6, which are respectively connected with 40 oscillating shafts 7. Attached to the opposite ends of these shafts 7 are the intermeshing cog-segments 8, which serve to operatively connect the two shafts, and these segments are preferably attached to the shaft 7 by means of 45 set-screws 9, which will enable the shafts to be so adjusted in the segments that they will cooperate to simultaneously act upon the ears 3 at opposite sides of the torpedo for pressing them downward. Connected to one of these 50 shafts 7 is a crank-arm 10, to the free end of

which is connected a rod 11. The opposite end of this rod 11 is connected with a foot-treadle 12, having one end journaled in a suitable step 14, attached to the floor. A spring 15 has its lower end connected to the 60 treadle 12 and its upper end connected with an adjustable bolt 16, which passes through a supporting-table 17, the latter being shown in dotted lines. This spring 15 by the adjusting-rod 16 can have its tension regulated as may be desired.

65 It will be observed that the recess 5 of the holder is of a depth substantially equal to the thickness of the torpedo, whereby it is not possible to crush the torpedo by the presser-arms 6 and cause an explosion thereof. Furthermore, the spring 15 is adjusted at a tension so that the operator cannot deliver a hammering blow to the torpedo.

In operation the torpedo is placed in the 70 holder with the ears 3 standing vertically, as shown in Fig. 3. The strap 4 is then placed between the ears. A downward pressure upon the treadle 12 closes the ears downward, and the operation is complete.

Having thus described my invention, what I claim, and desire to secure by Letters Patent, is—

1. A machine of the character described, comprising a torpedo-holder having a recess 85 of a depth substantially equal to the depth of the torpedo and a presser overlapping the holder to act on the projecting parts of the torpedo, the presser limited in its downward movement by the wall of the holder, for the 90 purpose described.

2. A machine for the purpose described, comprising a base having a torpedo-holder, oscillating shafts located in parallel lines at opposite sides of the holder, one end of the 95 shafts projecting at opposite sides of the holder, and above and out of contact with the base, and carrying presser-arms projecting normally away from the holder, and means for oscillating said shafts.

3. A machine of the character described, comprising a torpedo-holder, oscillating presser-arms located at opposite sides thereof and adapted to overlap the holder, means operatively connecting the said presser-arms, a 105 treadle operatively connected with one of the presser-arms, and an adjustable spring operatively connected with the treadle.

4. A machine of the character described, comprising a torpedo - holder, oscillating 110

shafts located in lines at opposite sides of the holder, the ends of the shafts adjacent the holder provided with upwardly-extending presser-arms, supported to permit the passage of a strap thereunder, the shafts provided with intermeshing gears, and means connected with one of the shafts for oscillating it, whereby both shafts are oscillated simulta-

neously in opposite directions and the presser-arms moved over the holder. 10

In testimony whereof I affix my signature in presence of two witnesses.

FRANK DUTCHER.
